ERNEST L. PATTEN, OF MALDEN, MASSACHUSETTS.

MACHINE FOR CUTTING SOLES.

1,270,319.

Specification of Letters Patent. Patented June 25, 1918.

Application filed February 19, 1917. Serial No. 149,412.

To all whom it may concern:

Be it known that I, ERNEST L. PATTEN, a resident of the city of Malden, in the county of Middlesex and Commonwealth of Massachusetts, have invented certain new and useful Improvements in Machines for Cutting Soles, of which the following is a specification.

My invention relates to that type of form cutting machines in which a knife is caused to traverse a sheet of rubber or the like for cutting soles therefrom, and in which the knife-carrying instrumentalities are moved in an oblong path, while the knife itself is controlled by a leader, as set forth in my U. S. Patent 1,144,429, issued June 29, 1915.

My present invention has for its objects, first, to give to the knife-carrying instrumentalities a bodily motion of translation as a whole, in addition to a similar motion of the leader; second, to provide an improved means for adjusting the travel of the instrumentalities and leader; third, to devise improved means whereby the work supporting table may be kept entirely stationary, while the working parts are raised for the insertion of the sheets of rubber or leather; and to effect other improvements in details of construction hereinafter set forth.

In the drawings forming part of this specification, Figure 1 is an elevation of a machine embodying my improvements, parts being broken away and in section. Fig. 2 is an end elevation of the same. Fig. 3 is an elevation on a larger scale of the knife carrying means. Fig. 4 is an elevation of the same from a different point of view, parts being in section. Fig. 5 is a perspective view of a group of allied parts. Fig. 6 is a perspective view of another group of allied parts. Fig. 7 is a plan view of the leader locking device. Fig. 8 is a cross section of the same.

The reference numeral 1 designates the machine table upon which the sheet material to be cut is laid; 2 is the knife by which the material is cut; and 3 is the form about whose periphery the knife is made to travel, the form being rigidly supported above the table by a stem 4 depending from a suitable frame-member 5.

The knife 2 is held by a carrier-arm 6

pivotaly supported at the end opposite the knife on a vertical bolt 7, the carrier-arm 55 being resiliently pressed against the stop 9 by a helical spring 10 whose torsional effect thereon is adjusted by the knurled annulus 11 and set screw 12, as illustrated in Figs. 3 and 4. An anti-friction roll 13 carried by the arm 6 and bearing against the under surface of the plate 14, takes the upward strain given to the knife during its cutting action, and permits it to swing freely about the curves of the form 3.

The plate 14 is rigid with a spindle 15 turning in bearings 17, 19, the latter being connected with a head 20 slidably supported on ways 21. The upper part of the head 20 is provided with spaced anti-friction rolls 22 movable in ways 23; the ways 21, 23 being united by posts 24. The ways 23 are formed with a faced plate 25 united by bolts 26 with an upper plate 27, which plates are slidale along the upper and under surfaces of the head 29, and the bolts are given anti-friction rolls 30 fitting the slot 31 in the head 29. An anti-friction roll 32 carried by the upper way-member 23 serves to withstand the lateral pressure 70 given by the knife 2. Anti-friction rolls 33, 34 and 35, 36 bearing against the vertical flange 37 of the leader 39 further guide the knife in its travel.

For propelling the knife frame, composed of above recited parts, with its guide rolls 30 traveling in the slot 31, sprocket chain 40 passing about sprocket wheels 41, 42 is connected to the upper plate 27 by a link 43. The sprocket wheel 42 is rotated 90 by bevel gears 44, 45.

The head 29, with its bonnet 46, is slidably supported by the frame 79 to be moved to the two extremes indicated by dotted lines in Fig. 1, and the means for such actuation comprises a shaft 47 rotated by spiral gears 49, 50 (Fig. 2), a face plate 51 (Fig. 5), a crank pin 52 whose head 53 is slidale in the dovetail groove 54 in the face plate, a block 55 on the crank pin vertically slidale in the slot 56 of the pitman 57.

For adjusting the throw of the crank pin 52, the face plate 51 has a rack 59 fastened thereto, with which meshes a pinion 105 mounted on a sleeve turning on the crank

pin and fastened in the hub of the knurled wheel 61. The outer end of the crank pin passes through a friction plate 62 and has a cam 63 pivoted thereon by a pin 64. By 5 forcibly turning the wheel 61, the pinion 60 causes the crank pin to travel along the groove 54 until it reaches the desired throw, and then the cam 63 is turned down to press the friction plate 62 against the 10 flanged rim of the wheel 61 hard enough to lock the latter against further movement.

To maintain the motion of the bevel gear 45, it is held against its associated gear 44 by having its shaft 65 supported in bearings 66, 67 carried by the head 29, the shaft being suitably held against longitudinal displacement in said bearings. In alignment with the shaft 65 is a shaft 69 connected therewith by flexible couplings 70 (Fig. 1) 20 and squared or otherwise made to be slideable in but to turn with a tubular shaft 71 which receives its power through a sprocket chain 72. Consequently, a continuous motion is communicated to the sprocket chain 40 and thence to the knife frame, notwithstanding the longitudinal reciprocation being given the head 29 by the crank pin 52. As shown in Fig. 2, the spiral gear 49 has its shaft 73 provided with a spur gear 74 25 meshing with a gear 75 mounted on the shaft 71.

The leader plate 39 having the vertical flange 37 about its inner periphery (see Figs. 1, 4 and 7) is slidably supported by a carrier 35 76 slideable in ways 77 held by the depending frame members 79 (Fig. 2). This carrier is moved by means of a pitman 80, and adjustable crank pin 81 practically identical with those above described for the head 29; the 40 shaft 82 carrying the face plate 83 which holds the crank pin 81, being provided with a gear 84 meshing with the gear 50.

For enabling the table 1 to be absolutely stationary and yet to permit the sheet material M to be readily introduced thereon beneath the form 3 and knife 2, I have devised means for suitably raising and lowering the entire operating mechanism and the frame members 85, 79 and 5 carrying the mechanism, without interfering with the operations. To this end, the table supporting means 86 is formed with vertical ways 87 (Figs. 1 and 2) in which the frame member is slideable. Springs 89 resiliently support 50 the frame members and operating mechanism in a normally elevated position to permit the easy introduction of the material M upon the table, and suitably actuated depressing means acting through a link 90 55 serves to depress the mechanism at the proper time and to the desired point for pressing the form 3 upon the material to be operated upon.

Inasmuch as the sprocket chain 72 connects with a suitable sprocket wheel 100 on

a shaft 101 (Fig. 2) carried by the fixed framework 86, while the sprocket wheel engaged by the upper part of said chain is carried on the vertically movable frame 85, it is necessary to provide a means for periodically taking up the slack in the chain during the frame's descent. For this purpose, an idler 102 is swung against the inner face of the sprocket chain by a bell-crank lever 103 pivotally supported at 104 and having its 70 arm 105 met by the end of a stud 106 projecting from the frame member, the pivot 104 being supported by the frame 86. Consequently, as the frame members 85, 79, 5 and the mechanism supported thereby, begin 75 to descend, the stud 106 swings the idler 102 outward, carrying with it the chain 72, and so takes up the slack which would otherwise occur therein.

Since there must be a frequent change in 85 leaders 39 in order to enable the machine to cut different sizes of shoe forms, it is essential that the locking means by which each leader is held in place shall be both sure in its grip, easy to manipulate, and in no way 90 an obstruction to the sheet rubber or other material being cut up. To this end, each side-member 76 of the leader carrier has an overhang 107 beneath which the corresponding edge of the leader is to fit, and a lug 109 95 upon which the said edge is supported, the edge being given a notch 110 so that the leader can be pushed up with the notch passing the lug and then be moved directly rearward until the latter comes beneath the unbroken edge and supports the same.

The leader is fastened in place by the locking block 111 slideable in the slot 112 in the carrier 76, and actuated by a lever 113 pivoted at 114 and engaging a pin 115 rising 105 from the block. The end of the block 111 being brought in front of the shoulder 116 of the leader, the latter is locked against withdrawal; and the block and lever are held in this position by a spring latch 117 adapted 110 to engage the corner of the carrier, as shown in Fig. 7. I prefer to provide the end of the block 111 with lips 119, 120 adapted to come above and below the surfaces of the carrier below the slot and thereby to support the end 115 of the block thereat, the other end of the block coming between the leaves of the ways 77. The lower lip 120 is constructed to come beneath the edge of the shoulder 116 and so to support the leader thereat.

The employment of the anti-friction rolls 13 and 32, is very important, the roll 13 taking the pressure of the knife while in operation and permitting the free swing of the arm 6 as the knife follows the sinuosities of the leader flange 37; and the roll 32 taking the strain of the lateral pressure against the entire knife carrying mechanism.

By having the leader frame 76 and the head 29 both made movable synchronously

with the travel of the knife frame as propelled by the chain 40, and such movements made adjustable both in extent and direction, the same machine is enabled to be used 5 for cutting all sizes of soles. In actual practice, I find it desirable to adjust the throw of the leader carrier with every change in size of sole to be cut; but the adjustment of the reciprocation of the head 29 needs to be 10 varied but three or four times. The crank pin 52 is set in alinement with the shaft 47, and hence with a zero-throw, when women's sizes of soles are to be cut; for children's and misses' soles, the crank pin is set to give a 15 minus throw,—that is, to move the head toward the left (as viewed in Fig. 1) when the knife-carrier is moving toward the right, and thereby to diminish the total movement of the knife.

20 For men's sizes of soles, the crank pin is adjusted to add its throw to that of the chain, instead of decreasing it as in children's sizes.

In each case, the leader-carrier must have 25 its throw correspondingly varied, and in addition, with each change in the sizes of children's soles, with each change in sizes of ladies' soles, and with each change in sizes of men's soles, the leader carrier must be adjusted.

30 My improvement whereby the entire operating machinery and its supporting frame are made to rise for permitting the sheet rubber to be introduced upon the work table 35 beneath the form 3, is also an important one, since otherwise to arrange for the ascent and descent of the form will require a complication of parts which not only adds materially to the expense of the machine, but to the dimensions of it as well.

40 My leader locking means above referred to is of considerable importance, not alone because of its ease and certainty of operation, but because it does not unduly rise 45 above the surface of the leader and interfere with the action of the knife carrying frame.

What I claim is:

1. A sole cutting machine comprising a 50 work table, a knife, means for moving the knife in an oblong path, a leader controlling the path of the knife, and means for periodically shifting the knife moving means in the direction of the major axis of the path, for 55 lengthening and shortening the path of the knife.

2. A sole cutting machine comprising a work table, a knife, means for moving the knife in an oblong path, a leader controlling 60 the path of the knife, and adjustable means for periodically shifting the knife moving means in the direction of its major axis.

65 3. A sole cutting machine comprising a work table, a knife, means for moving the knife in an oblong path, a leader controlling

the path of the knife, adjustable means for periodically shifting the knife moving means, and adjustable means for shifting the leader periodically.

4. A sole cutting machine comprising a 70 work table, a knife, means for moving the knife in an oblong path, and means for periodically shifting the knife moving means bodily, both said means moving in synchronism, and the second named means being capable of adjustment both in degree of movement and in direction.

5. A sole cutting machine comprising a work table, a knife, means for moving the knife in an oblong path and for controlling 80 the course of the knife, and means for synchronously shifting said means comprising a shaft and face plate, the face plate having a dovetail groove diametrically therein, a dovetail block slidable in said groove, a 85 crank pin projecting from said block parallel with said shaft, a pinion turning on said pin, a rack carried by the face plate in mesh with said pinion, a pitman connected with said pin and said means, a hand wheel on 90 said pin adapted for forcibly rotating said pinion, a friction plate resting against a face of said wheel, and a cam carried by the outer extremity of said pin and disposed for pressing said friction plate against the face 95 of said wheel and thereby locking the pinion and hence the crank pin at any desired point of adjustment.

6. A sole cutting machine comprising a fixed work table provided with vertical ways 100 at one end, a frame slidable in said ways, a knife, means for moving the knife in an oblong path, a leader controlling said path, and a form for guiding the knife and holding the work upon the table, and mechanism 105 for actuating the knife moving means, said knife moving means, leader, form and mechanism being supported by and rising and falling with said frame.

7. A sole cutting machine comprising a 110 fixed work table having vertical ways, a frame slidable in said ways, a knife, means for moving the knife in an oblong path, said means including a shaft and sprocket wheel, 115 said knife and knife moving means, shaft and sprocket wheel being supported by and rising and falling with said frame, a power driven sprocket wheel having stationary bearings below said frame, a sprocket chain joining said sprocket wheels, an idler resting against said chain, a bell-crank lever carrying said idler and having a stationary pivot, and a projection from said frame adapted to engage said bell-crank lever and to cause its idler to flex said chain and thereby take up the slack therein as said frame descends, said frame having means for forcibly reciprocating it.

8. A sole cutting machine comprising a 120 knife and knife operating mechanism, a 125

leader controlling the knife, and a carrier supporting the leader, the leader having a notch in each of two opposing side edges, and the carrier having at each of said sides 5 of the carrier an overhung flange and an underhung lug, whereby the leader can be pressed up against the overhung flanges and

thence backward to present its unbroken edges above said lugs.

In testimony that I claim the foregoing 10 invention, I have hereunto set my hand this 16th day of February, 1917.

ERNEST L. PATTEN.
